RAILWAY CAR JOURNAL BOX CONSTRUCTION
Malcolm S. Johnson, Flossmoor, Ill., assignor to Illinois
Railway Equipment Company, Chicago, Ill., a corpora-
tion of Illinois
Continuation of application Ser. No. 724,354, Mar. 27,
1958. This application Feb. 5, 1962, Ser. No. 171,242
13 Claims. (Cl. 308—49)

This invention relates, generally, to the construction of railway car journal boxes and it has particular relation to means for centering axle journals therein. This application is a continuation of application Serial No. 724,354, filed March 27, 1958, now abandoned.

Among the objects of this invention are: To provide for mounting journal guides in a railway car journal box in a new and improved manner; to secure journal guides to the spaced vertical side walls of a journal box by a key that is insertable and removable endwise parallel to the axis of rotation of the axle; to hold the key in locking position; to employ an elongated flexible and resilient key and to apply it in locking position in an undulating manner; to provide journal guide support means on each side wall each arranged to receive a journal guide in interfitting relation; to arrange the interfitting relation in such manner as to provide an aperture for receiving the key therethrough; to provide the support means as a separate element and weld it to the inner side of each side wall; and to form the support means, in part, integrally with the journal box when it is cast.

Other objects of this invention will, in part, be obvious and in part appear hereinafter.

This invention is disclosed in the embodiments thereof shown in the accompanying drawings and it comprises the features of construction, combination of elements and arrangement of parts that will be exemplified in the constructions hereinafter set forth and the scope of the application of which will be indicated in the appended claims.

For a more complete understanding of the nature and scope of this invention reference can be had to the following detailed description, taken together with the accompanying drawings, in which:

FIG. 1 is a vertical sectional view, taken generally along the line 1—1 of FIG. 2, and showing a railway car journal box in which the present invention is embodied.

FIG. 2 is a horizontal sectional view taken generally along the line 2—2 of FIG. 1.

FIG. 3 is a vertical sectional view taken generally along the line 3—3 of FIG. 2.

FIG. 4 is a top plan view of one of the journal guide supports that is arranged to be welded to one of the vertical side walls of the journal box, the other journal guide support being of similar construction but opposite hand.

FIG. 5 is a view, in front elevation, of the journal guide support shown in FIG. 4.

FIG. 6 is a horizontal sectional view taken generally along the line 6—6 of FIG. 5.

FIG. 7 is a view, in end elevation, of the journal guide support shown in FIG. 6.

FIG. 8 is a top plan view of a journal guide which can be inserted in either of the journal guide supports on the opposite walls of the journal box.

FIG. 9 is a view, in front elevation, of the journal guide shown in FIG. 8.

FIG. 10 is a horizontal sectional view taken generally along the line 10—10 of FIG. 9.

FIG. 11 is a plan view of a flexible resilient elongated key that is employed for securing each of the journal guides in its support.

FIG. 12 is a view, in side elevation, of the key shown

2

in FIG. 11 and illustrating the key lock applied thereto for securing it in operative position in the journal box.

FIG. 13 is a vertical sectional view taken generally along the line 13—13 of FIG. 14 and shows a modification of the invention.

FIG. 14 is a horizontal sectional view taken generally along the line 14—14 of FIG. 13.

FIG. 15 is a vertical sectional view taken generally along the line 15—15 of FIG. 13; and

FIG. 16 is a fragmentary elevational view taken generally along the line 16—16 of FIG. 14.

Referring now particularly to FIGS. 1, 2 and 3 of the drawings, it will be observed that the reference character 10 designates, generally, a railway car axle which is provided with an axle journal 11 that has at its outer end an end collar 12 which extends radially beyond the bearing surface of the journal 11. The longitudinal axis of rotation of the axle 10 is indicated at 13. The longitudinal axis 13 is employed as a reference base in defining the invention in certain of the claims.

The axle journal 11 extends into a railway car journal box that is indicated, generally, at 14 and it forms an integral part of a side frame of a railway car truck. The journal box 14 includes a top 15, a bottom 16 and vertical side walls 17 and 18. Positioned within the journal box 14 is a journal bearing 19 that rests upon the upper side of the axle journal 11 and is held in position by a wedge 20.

It is desirable to prevent movement of the axle journal 11 out of the journal bearing 19 which tends to take place during the starting or stopping of a train or at any time when there is a change in its speed. It is to provide for guiding the axle journal 11 within the journal box 14 and centering it substantially in the position shown under the

35 journal bearing 19 that this invention is particularly addressed. For this purpose there is provided on the vertical side wall 17 a journal guide support that is indicated, generally, at 23. Preferably the journal guide support 23 is a steel forging and it is welded at 24, 25 and 26,

40 FIG. 3, to the inner side of the vertical side wall 17. It will be observed that the welds 24, 25 and 26 are spaced from the central portion of the vertical side wall 17 or at locations outside of the critical zone where heat treatment is required if welding takes place. The journal guide support 23 is of sufficient length to permit the location of these welds outside of the critical zone. Thus the journal guide support 23 can be applied to journal boxes 14 that are in service without requiring that the side frames be heat treated or annealed.

50 A journal guide support, shown generally at 27, is mounted on and secured by welding to the vertical side wall 18. Like the journal guide support 23 it is a steel forging and is similar in all respects except that it is arranged for opposite hand mounting. Since its details of construction are otherwise identical with those of the journal guide support 23, only the latter will be described in detail herein.

FIGS. 4, 5, 6 and 7 of the drawings show the details of construction of the journal guide support 23. As pointed out above it is formed preferably of a steel forging and it has an elongated lower part 30 which is provided with a depending flange 31. Formed integrally with the elongated part 30 are end bridging portions 32 and 33 and an intermediate bridging portion 34. The portions 32, 33 and 34 together with the elongated part 30 provide a groove 35 which extends parallel to the axis 13 of rotation of the railway car axle 10. The side of the groove 35 opposite the elongated part 30 is formed by flange portions 36, 37 and 38 that are formed integrally with the bridging portions 32, 33 and 34, respectively. The bottom of the groove 35 is indicated in FIG. 6 at 40, 41 and 42 on the bridging portions 32, 33

and 34, respectively. It will be observed that the bottom 42 of the groove 35 on the intermediate bridging portion 34 is convex and that the bottom of the groove 35 faces away from the axis 13 of rotation of the railway car axle 10. The end bridging portion 33 is provided with a flange or end wall 45 while the end bridging portion 32 has a recess 46 formed in the bottom 40 for the purposes that will presently be apparent.

Interfitting with each of the journal guide supports 23 and 27 is a journal guide that is indicated, generally, at 47. The journal guides 47 are of identical construction and preferably are formed of press forged bronze. The details of construction are shown in FIGS. 8, 9 and 10 of the drawings. It will be observed that the journal guide 47 is provided with a bearing face 48 along one side which is juxtaposed to the surface of the axle journal 11. As shown in FIG. 1 the bearing faces 48 are located at diametrically opposite sides of the axle journal 11 in a horizontal plane through the axis 13 of rotation. Projections 49 are formed integrally on the other side of the journal guide 47 and they extend into the groove 35 previously described as being formed in the respective guide supports. The projections 49 are positioned between end sections 50 of the journal guide 47 and an intermediate section 51 which carry on one side the bearing face 48 previously referred to. Ribs 52 extend between the end sections 50 and the intermediate section 51 and a vertical groove 53 may be provided midway the ends of the intermediate section 51 in the bearing face 48. Side walls 54 are formed integrally with the journal guide 47 and support the projections 49.

Since the projections 49 extend into the groove 35 in the journal guide support 23 and the bearing face 48 is juxtaposed to the axle journal 11, the surfaces 55 of the projections 49 face toward the axle journal 11 or toward its axis 13 of rotation. These surfaces 55 are beveled as indicated at 56 and 57 for a purpose that presently will be apparent.

It will now be understood that the bottom and sides of the groove 35 extending lengthwise of the journal guide support 23 and the surfaces 55 on the projections 49 define what can be considered as an aperture which extends parallel to the side wall 17 for example, and longitudinally of the axle journal 11 and parallel to its axis 13 of rotation. Advantage is taken of the provision of this aperture for inserting a flexible resilient elongated key 59 therein as shown in FIG. 2 of the drawings. The key 59 itself is shown in FIGS. 11 and 12. It is provided with a rounded end 60 to facilitate insertion in the aperture previously described. In order to further facilitate its insertion the intermediate bridging portion 34 is provided with the convex bottom 42 and each of the projections 49 is provided with the beveled surface 56 or 57 one or the other of which may be engaged by the rounded end 60 of the key 59 depending upon which way the journal guide 47 is applied to the journal guide support 23.

Referring again to FIG. 2, it will be observed that the key 59 is inserted in an undulating manner due to the fact that the bottom of the groove 35 formed by the central portion of the surface 42 is offset from the surfaces 40 and 41 toward the respective side wall 17 or 18, as shown in FIGS. 2 and 6 of the drawings, and for this reason and since it is resilient, being formed preferably of spring steel, it provides a holding biasing action to secure the journal guide 47 in position in the journal guide support 23. The extent that the key 59 can be inserted in the aperture along the bottom of the groove 35 is controlled, in part, by the flange or end wall 45.

In order to prevent inadvertent or accidental withdrawal of the key 59 it is provided, as shown in FIG. 11, with a slot 61 in which a key lock 62 is positioned. It will be noted that the key lock 62 extends from opposite sides of the key 59 and that one side, as shown in FIG. 2, is arranged to interfit with the recess 46. In order

to withdraw the key 59, as shown in the lower part of FIG. 2, it is necessary to spring the key 59 toward the respective side wall, for example the wall 18, in order to clear the key lock 62 from the recess 46. Then a suitable tool can be inserted in an aperture 63 near the outer end of the key 59 and sufficient tension be applied to withdraw it.

In operation, with the axle journal 11 removed, the guide supports 23 and 27 are properly located along the vertical side walls 17 and 18, respectively, of the journal box 14 and then are welded in place in a manner previously described. Since the welding takes place away from the central portions of the side walls 17 and 18 and particularly from the central portion of the side wall 17, it is unnecessary to heat treat the car side frame after the journal guide supports 23 and 27 have been welded in position.

Next the car side frames can be assembled with the axle journals 11 but without the journal bearing 19 and wedge 20. The journal guides 47 can be inserted over the end collar 12 and the upper surface of the axle journal 11 and then moved downwardly on either side into position in the respective journal guide support 23 or 27. This is permitted since the elongated part of the journal guide support 23 extends only along the bottom, there being openings between the intermediate bridging portion 34 and the bridging portions 32 and 33 spaced from its ends. The projections 49 enter these openings and the journal guide 47 is properly located. Then the key 59 is inserted in the aperture along the bottom of the groove 35, previously described, until the rounded end 60 engages the flange or end wall 45. The end bridging portion 32 is beveled, as indicated at 64, in order to facilitate the passage of the key lock 62 when the key 59 is inserted. When the key 59 is inserted, it is guided into proper position along the groove 35 over the surface 40 of the bridging portion 32, over the surface 55 of the first projection 49, then over the convex bottom 42 of the intermediate bridging portion 34, over the beveled surface 56 leading to the surface 55 on the other projection 49, and finally over the surface 41 of bridging portion 33. The spacing is such and the thickness of the key 59 is enough to cause it to follow the undulating movement described on insertion and to remain in a wavy position as shown in FIG. 2. Not only does the key 59 securely hold the journal guide 47 in position but also it does so with a biasing action and thus prevents any rattling that might take place if the key 59 were loose.

FIGS. 13, 14, 15 and 16 show another embodiment of the invention. It is intended for use in the construction of railway car journal boxes 14 when they are originally manufactured rather than for addition thereto as is the case for the construction previously described and illustrated in FIGS. 1 to 12 inclusive. Insofar as possible the same reference characters will be employed in FIGS. 13 to 16 that were previously used.

Referring particularly to FIG. 16 it will be noted that the upper and lower guide bosses 66 and 67 are cast integrally with the vertical side wall 17. Similar bosses are cast integrally with the vertical side wall 18 and need not be described further. The guide bosses 66 and 67 are formed with central recesses 68 and 69 for receiving bosses 70 and 71 that are formed integrally along the upper and lower edges of an adapter plate 72 that preferably is a steel forging. As shown in FIGS. 13 and 14 of the drawings the adapter plate 72 is welded as indicated at 73 and 74 to the upper and lower guide bosses 66 and 67. After the welding operation is performed at 73 and 74, the side frame is annealed to relieve any stresses that might have been set up because of the welding operations.

FIG. 14 shows a cross section of the adapter plate 72. It will be noted that it is provided with a convex surface 77 which faces away from the axis 13 of rota-

tion of the railway car axle 10 and forms the bottom of a groove 78 the sides of which are provided by the guide bosses 66 and 67. The groove 78 corresponds to the groove 35 previously described.

Mounted on each journal guide support provided by the upper guide bosses 66 and 67 and the adapter plate 72 is a journal guide 81. Preferably it is formed of press forged bronze and it has a bearing face 82 which is positioned adjacent the surface of the axle journal 11 in a manner similar to that described for the bearing face 48 described hereinbefore. Each journal guide 81 includes projections 83 that are located beyond the ends of the adapter plate 72. The projections 83 are connected by side walls 84 to the central portion of the journal guide 81. The projections 83 have surfaces 85 which face toward the axis 13 and together with the surface 77 of the adapter plate 72 provide a longitudinally extending aperture parallel to the axis 13 for the purpose of receiving a key in the manner described previously. In order to facilitate application of the key the projections 83 are beveled as indicated at 86 and 87 on opposite sides of the surface 85. The key is indicated at 88 and, as previously described, it is formed of spring steel and is a flexible resilient elongated member. Because of the provision of the convex surface 77, the aperture defined thereby and by the surfaces 85 is offset at its intermediate portion from the end portions with the result that, as shown in FIG. 14, the key 88 extends along this aperture in an undulating manner.

At one end the key 88 is provided with a head 89 having a detent 90 that is arranged to interfit with a groove 91 which is formed in a stop 92 that is cast integrally with the respective side walls 17 or 18. Since the detent 90 interfits with the groove 91, movement in either direction of the key 88 is prevented. The other end 93 of the key 88 is rounded to facilitate entry into the aperture provided along the bottom of the groove 78.

With a view to limiting the extent of downward movement of the journal guides 81 when they are inserted, stops 94 are cast integrally with the respective side walls 17 and 18 at the ends of the lower guide boss 67. The projections 83 engage the upper sides of the stops 94 when they are assembled in the manner previously described and thus serve to locate the journal guides 81 for insertion of the key 88 in the undulating manner. An inclined surface 96 is provided for each stop 92 to facilitate the insertion of the key 88 and particularly to deflect the detent 90 to a position where it can enter the respective groove 91.

Since the application of the journal guides 81 in the assembly shown in FIGS. 13, 14 and 15 is essentially the same as described for the preceding figures, it will not be repeated.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In combination, a railway car journal box having spaced vertical side walls and an axle journal spaced from said side walls, journal guide support means on the inner side of each side wall extending toward said axle journal and having a journal guide support surface facing said axle journal and a keyway having a non-circular cross section on the opposite side, a journal guide having spaced projections on one side extending toward each side wall beyond the respective keyway in and straddling said journal guide support means and a surface overlying and bearing against said support surface and on the opposite side having a bearing face juxtaposed to diametrically opposite sides of said axle journal whereby

thrust applied to said bearing face is transmitted through the respective journal guide support surface to the corresponding vertical wall of the car journal box, said spaced projections each having a keyway in said journal guide support means and constituting an endwise extension thereof with the composite keyway extending generally parallel to the axis of rotation of said axle journal, and resilient key means having a non-circular cross section substantially filling each composite keyway and interfitting with each journal guide support means and the journal guide interfitting therewith to hold the latter stationary and in operative position on the former.

2. In combination, a railway car journal box having spaced vertical side walls and an axle journal spaced from said side walls, journal guide support means on the inner side of each side wall extending toward said axle journal and having a journal guide support surface facing said axle journal and a keyway having a non-circular cross section on the opposite side, a journal guide having spaced projections on one side extending toward each side wall beyond the respective keyway in and straddling said journal guide support means and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, said spaced projections each having a keyway of non-circular cross section aligned with said keyway in said journal guide support means and constituting an endwise extension thereof with the composite keyway extending generally parallel to the axis of rotation of said axle journal, the intermediate portion of said composite keyway on said journal guide support means being offset toward the respective vertical wall of the car journal box from the portions of said composite keyway on said projections, and an elongated resilient key having a non-circular cross section and extending along each composite keyway in an undulating manner to hold each journal guide stationary and in operative position on the respective journal guide support means.

3. In combination, a railway car journal box having spaced vertical side walls and an axle journal spaced from said side walls, journal guide support means on the inner side of each side wall extending toward said axle journal and having a journal guide support surface facing said axle journal and a keyway having a non-circular cross section on the opposite side, a journal guide having spaced projections on one side extending toward each side wall beyond the respective keyway in and straddling said journal guide support means and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, said spaced projections each having a keyway of non-circular cross section aligned with said keyway in said journal guide support means and constituting an endwise extension thereof with the composite keyway extending generally parallel to the axis of rotation of said axle journal, the intermediate portion of said composite keyway on said journal guide support means being offset toward the respective vertical wall of the car journal box from the portions of said composite keyway on said projections, an elongated resilient key having a non-circular cross section and extending along each composite keyway in an undulating manner to hold each journal guide stationary and in operative position on the respective journal guide support means, and locking means on said journal box cooperating with said key and holding it against endwise movement in said composite keyway.

4. In combination, a railway car journal box having spaced vertical side walls and an axle journal spaced from

said walls, journal guide support means on the inner side of each side wall in horizontal aligned relation with the axis of rotation of said axle journal and spaced from the diametrically opposite sides thereof and having a journal guide support surface facing said axle journal, each support means providing a groove extending generally parallel to said axis with one or more bridging portions overlying the respective groove and providing the bottoms thereof facing away from its journal guide support surface, a journal guide having a pair of spaced projections on one side extending toward each side wall beyond the respective groove in said journal guide support means, a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, each projection having a groove aligned with said groove in said journal guide support means and constituting an endwise extension thereof with the composite groove extending generally parallel to said axis of rotation of said axle, and elongated resilient key means in each composite groove underlying said projection or projections and overlying said bridging portion or portions to hold each journal guide in operative position.

5. In combination, a railway car journal box having spaced vertical side walls and an axle journal spaced from said walls, journal guide support means on the inner side of each side wall in horizontal aligned relation with the axis of rotation of said axle journal and spaced from the diametrically opposite sides thereof and having a journal guide support surface facing said axle journal, each support means providing a groove extending generally parallel to said axis with one or more bridging portions overlying the respective groove and providing the bottoms thereof facing away from its journal guide support surface, a journal guide having a pair of spaced projections on one side extending toward each side wall beyond the respective groove in said journal guide support means, and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, each projection having a groove aligned with said groove in said journal guide support means and constituting an endwise extension thereof with the composite groove extending generally parallel to said axis of rotation of said axle, said journal guide support means being generally E-shaped with the arms extending upwardly to receive said projections on said journal guide therebetween from above, the intermediate portion of said composite groove on said journal guide support means being offset toward the respective vertical wall of the car journal box from the portions of said composite groove on said projections, and an elongated resilient key extending along each composite groove in an undulating manner to hold each journal guide stationary and in operative position on the respective journal guide support means.

6. In combination, a railway car journal box having spaced vertical side walls and an axle journal spaced from said walls, journal guide support means on the inner side of each side wall in horizontal aligned relation with the axis of rotation of said axle journal and spaced from the diametrically opposite sides thereof and having a journal guide support surface facing said axle journal, each support means providing a groove extending generally parallel to said axis with one or more bridging portions overlying the respective groove and providing the bottoms thereof facing away from its journal guide support surface, a journal guide having a pair of spaced pro-

jections on one side extending toward each side wall beyond the respective groove in said journal guide support means, and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, each projection having a groove aligned with said groove in said journal guide support means and constituting an endwise extension thereof with the composite groove extending generally parallel to said axis of rotation of said axle, said journal guide support means being generally E-shaped with the arms extending upwardly to receive said projections on said journal guide therebetween from above, the intermediate portion of said composite groove on said journal guide support means being offset toward the respective vertical wall of the car journal box from the portions of said composite groove on said projections, and an elongated resilient key extending along each composite groove in an undulating manner to hold each journal guide stationary and in operative position on the respective journal guide support means, means providing a locking shoulder on each key, and cooperating shoulder means on each journal guide support means engaging each locking shoulder and holding each key against endwise movement along said composite groove.

7. In combination, a railway car journal box having spaced vertical side walls and an axle journal spaced from said side walls, an elongated journal guide support separate and distinct from and welded to the inner side of each side wall and positioned at the level of the axis of rotation of said axle journal and having a journal guide support surface facing said axle journal and a keyway having a non-circular cross-section on the opposite side, a journal guide having spaced projections on one side extending toward each side wall beyond the respective keyway in and straddling said journal guide support means and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, said spaced projections each having a keyway of non-circular cross section aligned with said keyway in said journal guide support means and constituting an endwise extension thereof with the composite keyway extending generally parallel to the axis of rotation of said axle journal, resilient key means having a non-circular cross-section substantially filling each composite keyway and interfitting with each journal guide support means and the journal guide interfitting therewith to hold the latter stationary and in operative position on the former, said composite keyway having flat oppositely facing vertical generally parallel surfaces with its intermediate portion being offset toward the respective vertical wall of the car journal box from the portions of said composite keyway on said projections, and an elongated resilient key having flat opposite sides extending along said composite keyway in an undulating manner and holding said journal guide in operative position on said support.

8. In combination, a railway car journal box having spaced vertical side walls and an axle journal spaced from said side walls, an elongated journal guide support separate and distinct from and welded to the inner side of each side wall and positioned at the level of the axis of rotation of said axle journal and having a journal guide support surface facing said axle journal and a keyway having a non-circular cross-section on the opposite side, a journal guide having spaced projections on one side extending toward each side wall beyond the respective keyway in and straddling said journal guide support means and a surface overlying and bearing against said support surface and on the opposite side having a bearing face

juxtaposed to diametrically opposite sides of said axle journal whereby thrust applied to said bearing face is transmitted through the respective journal guide support surface to the corresponding vertical wall of the car journal box, said spaced projections each having a keyway of non-circular cross-section aligned with said keyway in said journal guide support means and constituting an endwise extension thereof with the composite keyway extending generally parallel to the axis of rotation of said axle journal, said composite keyway having flat oppositely facing vertical generally parallel surfaces with its intermediate portion being offset toward the respective vertical wall of the car journal box from the portions of said composite keyway on said projections, and an elongated resilient key having flat opposite sides extending along said composite keyway in an undulating manner and holding said journal guide in operative position on said support.

9. In combination, a railway car journal box having spaced unperforated vertical side walls and an axle journal spaced from said side walls, inwardly extending upper and lower guide bosses integral with each side wall and extending generally parallel to and respectively above and below a horizontal plane through the axis of rotation of said axle journal, a journal guide support in the form of an adapter plate welded along its upper and lower edges to each set of upper and lower guide bosses and having a journal guide support surface facing said axle journal and a keyway on the opposite side, a journal guide having spaced projections on one side extending toward each side wall beyond the respective keyway in and straddling said journal guide support and a surface overlying and bearing against said support surface and on the opposite side having a bearing face juxtaposed to diametrically opposite sides of said axle journal whereby thrust applied to said bearing face is transmitted through the respective journal guide support surface to the corresponding vertical wall of the car journal box, said spaced projections having a keyway aligned with said keyway in said journal guide support and constituting an endwise extension thereof with the composite keyway extending generally parallel to the axis of rotation of said axle journal, and an elongated key extending along each composite keyway and interfitting with each journal guide support and the journal guide interfitting therewith to hold the latter stationary and in operative position on the former.

10. The combination with a railway car journal box including a crown, vertical side walls each having inner and outer faces, and a bottom, of a horizontal railway car axle having an end part positioned in the journal box and which provides a journal portion, means providing a solid bearing between said crown and said journal portion, at least one journal stop positioned between the inner face of the journal box side wall and said journal portion, and means detachably holding said journal stop in position on the associated side wall of the journal box, said journal stop having an impact face located adjacent to but normally out of contact with the adjacent journal portion in a position to be contacted by that adjacent part of said journal portion upon a shifting of the journal portion laterally of the journal box to a predetermined extent and prevent further lateral shifting, said journal stop holding means comprising front and rear structural formations spaced longitudinally of the journal box inner face side wall and projecting inwardly therefrom, rear portions of said journal stop being located between said structural formations, and means within, extending longitudinally of and engaging said structural formations, said last-mentioned means engaging said journal stop outwardly of the impact face thereof and retaining said

journal stop in operative position, whereby shifting of the journal stop in any direction is prevented.

11. The combination with a railway car journal box including a crown, vertical side walls each having inner and outer faces, and a bottom, of a horizontal railway car axle having an end part positioned in the journal box and which provides a journal portion, means providing a solid bearing between said crown and said journal portion, at least one journal stop means positioned between the inner face of the journal box side wall and said journal portion, and means detachably holding said journal stop means in position on the associated side wall of the journal box, said journal stop means having a pair of bearing faces located adjacent to but normally out of contact with the adjacent journal portion in a position to be contacted by that adjacent part of said journal portion upon a shifting of the journal portion laterally of the journal box to a predetermined extent and prevent further lateral shifting, said journal stop holding means being secured to said inner face side wall and comprising an elongated part forming a bottom wall with upstanding front and rear structural formations spaced longitudinally of said journal box inner face side wall and projecting inwardly therefrom and providing a pair of upwardly and inwardly opening slots, rear projections on said journal stop means extending into said slots, and retaining means extending endwise of said journal stop holding means along said structural formations and said rear projections and reacting therebetween to hold said journal stop means in operative position on said journal stop holding means.

12. Journal stop mechanism comprising a support bracket, said support bracket including a pair of spaced slots each having a bottom and upstanding sides, aligned openings formed in said upstanding sides, stop block means removably fitted with each of said slots, an opening formed through said stop block means adapted to be aligned with said openings in said upstanding sides of said slots, a retaining means for reception through the aligned openings in said upstanding sides of said slots and the stop block means for retaining the stop block means in operative position, and locking means for maintaining the retaining means in operative position.

13. Journal stop mechanism comprising a support bracket having a pair of spaced slots each having a bottom and upstanding sides with aligned openings in said upstanding sides, stop block means slidably fitted within each of said slots and extending outwardly of said support bracket, said stop block means having openings formed therethrough in alignment with said openings in said upstanding sides of said slots, an elongated locking pin extending through the aligned openings in said stop block means and said upstanding sides for retaining the stop block means in operative position, and locking means for maintaining said locking pin in operative position such that said stop block means may be quickly and easily removed from the support bracket by removing the locking pin.
